BURIAL RECEPTACLE

Robert L. Taylor, Aspinwall, Pa.

Application August 4, 1936, Serial No. 94,123

1 Claim. (Cl. 27—3)

My invention relates to a burial receptacle of the type employed for housing and protecting a casket or coffin, immediately inclosing a corpse, from the period of interment.

Important objects and advantages of the present invention are to provide a durable burial receptacle of the character described, which will indefinitely withstand the attendant destructive effects of underground burial, which is comparatively light in weight, attractive in appearance, and inexpensive to manufacture.

With the foregoing and other objects in view which will appear as the description proceeds, the invention consists of the novel construction, combination and arrangement of parts herein specifically described and illustrated in the accompanying drawing, but it is to be understood that changes in the form proportions and details of construction may be resorted to that come within the scope of the claim hereunto appended.

In the drawing wherein like numerals of reference designate corresponding parts throughout the several views:

Figure 1 is a side elevational view of a burial receptacle constructed in accordance with the invention.

Figure 2 is a transverse sectional view on line 2—2, Figure 1, and Figures 3 and 4 are similar views of modified embodiments of the present invention.

Referring in detail to the drawing 1 denotes the entire receptacle, which comprises an oblong, rectangularly-shaped, hollow case 2 having an open top, and including a cover 3 for the latter. The receptacle is constructed of wood, which has been impregnated with creosote, or treated with other agents of equivalent preservative properties. The cover is preferably transversely curved or arch-shaped to render same more capable of readily sustaining the load of the earth thereon upon interment.

The case 2 and its cover 3 have an interfitting tongue and groove engagement, respectively indicated at 4 and 5, which are preferably substantially V-shaped, and extend continuously throughout and along the contacting edges of said case and cover.

The entire interior wall surface of the receptacle 1 is provided with a lining 6, which is securely and permanently cemented in position throughout its area. The lining is constructed of substantial moisture proof material, not unlike ordinary rubberized composition roofing material, or of any other suitable sheet material.

The entire exterior surface of the receptacle 1, and the entire exposed surface area of the lining 6, are completely covered with coatings 7 of

asphaltic cement, which in turn, are covered by coatings 8 of paint, preferably special aluminum paint having high protective qualities.

The receptacle 1 is suitably sealed by a plastic asphaltic cement 9, which is interposed between the interfitting tongue and groove engagement of the case 2 and cover 3.

The modified form of the invention, illustrated in Figure 3, comprises a receptacle 10, constructed of two-ply of wood, respectively indicated at 11 and 12, which are rigidly secured together, with an interposed ply of suitable porous sheet material 13, in the form sheet felt and the like, disposed therebetween. The porous ply 13 is employed to create an air space between the wood plies 11 and 12, and thereby aid in the preservation of the structure. The wood plies are treated with a preservative agent, and the inner and outer surfaces of the entire receptacle are covered by coatings of asphaltic cement and paint, as set forth relatively to the disclosure in Figure 2.

The modification of the invention, shown in Figure 4, differs from the embodiment disclosed in Figure 2 and herein before described, in that the receptacle 14 is not only provided with a similar lining 15 on its inner surface, but also has its entire outer surface covered by a facing 16 of the same material. The lining 15 and facing 16 are securely and permanently cemented in position throughout their areas, and have their entire surface areas covered by coatings of cementitious material and paint, in the manner stated relatively to the disclosure in Figure 2.

The present invention provides an attractive, light, durable and inexpensive burial receptacle, which is impervious to moisture and constructed to readily and indefinitely withstand deterioration against the natural process of decomposition of the corpse contained therein, and against all conditions concomitant with underground interment, and which, owing to its durability, will entirely eliminate sunken graves due to the collapse of the burial structures.

What I claim is:

A burial receptacle of the character described comprising the combination of a case including bottom, side, and end members permanently secured together, and further including an interfitting cover member, each of said members being constructed of two plies of rigid sheet material having a sheet of porous material disposed therebetween to provide air space throughout the area of said two plies of rigid sheet material, and a coating of preservative material applied to the entire outer surface of said case.
